UNITED STATES PATENT OFFICE.

WILLIAM R. MCCLAVE, OF SCRANTON, PENNSYLVANIA, ASSIGNOR TO MCCLAVE-BROOKS COMPANY, OF SCRANTON, PENNSYLVANIA, A CORPORATION OF PENNSYLVANIA.

FURNACE CONSTRUCTION.

1,318,580.

Specification of Letters Patent.

Patented Oct. 14, 1919.

Application filed January 18, 1917. Serial No. 142,273.

To all whom it may concern:

Be it known that I, WILLIAM R. MCCLAVE, a citizen of the United States, residing at Scranton, in the county of Lackawanna and 5 State of Pennsylvania, have invented certain new and useful Improvements in Furnace Construction; and I do hereby declare the following to be a full, clear, and exact description of the same, reference being had to 10 the accompanying drawings, forming part of this specification.

This invention relates to improvements in furnace construction which are particularly useful in connection with furnaces for the 15 burning of bituminous coal and of the type utilizing the under-feed principle of stoking the fire. A furnace of this type is illustrated in the application filed by William McClave, December 20, 1916, Serial No. 20 138,043, and the present improvements are conveniently embodied in a furnace similar in many respects to the furnace illustrated and described in the William McClave application.

25 In said William McClave application there is shown and described a furnace provided with a fuel receiving channel inclosed within the front wall of the furnace and extending substantially clear across the fuel 30 receiving end of the grate. Fuel is fed to the channel by means of a chute and beneath the discharge end of the chute is located a pivoted sweep or swinging plate which may be swung back and forth by power connections or by hand to push the fuel transversely into the channel which extends from 35 both sides of the chute. After such transverse distribution of the fuel in the channel has been effected, the fuel is pushed down 40 onto the grate either by power operated rams or specially constructed hand tools. An object of the present invention is to provide a construction for feeding the fuel by gravity to the inclosed channel in such a way that the 45 fuel will distribute itself transversely in the channel without the necessity of employing power or hand operated sweeps for effecting transverse distribution of the fuel, such as is disclosed in the William McClave application.

50 A further object of the invention is to construct the fuel feeding mechanism for the inclosed channel in such manner that the feeding mechanism may be located in front 55 of the furnace and at the same time fire

doors may be located in the front furnace wall in positions which will permit ready access to the combustion chamber of the furnace without interference by the fuel feeding mechanism. The usual construction is 60 to provide fuel hoppers which extend clear across the front of the furnace, thereby practically blocking the way for the introduction of fire doors in the front furnace wall and making it exceedingly difficult to reach the 65 combustion chamber of the furnace when it becomes necessary to insert a tool for some purpose, such as to ram the fuel down the grate. By the present improved construction of fuel feeding mechanism this difficulty 70 is entirely obviated and no interference whatever is offered to access to the interior of the furnace through fire doors.

Furnaces of the type especially amenable to the present improvements vary considerably in width. For example, the furnace may be an exceedingly narrow one having but a single comparatively narrow combustion chamber, or the furnace may be very 75 wide and have a correspondingly wide combustion chamber or consist of many combustion chambers arranged one after the other in a long row. It is intended that the present improved mechanism for feeding fuel to the channel be utilized in furnaces 80 of widths ranging from the very narrowest to the widest, having several combustion chambers, and in order to avoid the necessity of specially constructing the fuel feeding mechanism for each individual furnace, 85 the feeding mechanism, in accordance with the preferred mode of practising the invention, is constructed in sections, each section constituting a unit which may be readily assembled with any number of other units 90 in order to provide means for delivering the fuel at a sufficient number of different points to meet the exigencies of the particular furnace, which it is desired to equip with the fuel feeding mechanism. Preferably, these 95 are different size units adapted to constitute the feeding mechanism, having a different number of points of discharge for the fuel, so that a feeding mechanism may be quickly 100 built up to meet widely variant conditions, 105 as to feed of fuel and size of the channels. For example, the units may be constructed in two different sizes, one having three points of discharge for the fuel and the other having but two, and by proper selection of these 110

units, a system forming the fuel feeding mechanism may be built up to accommodate a furnace of almost any width.

With the above and other objects in view, the invention consists in certain novel constructions, arrangements, and combination of parts hereinafter described in a preferred form and particularly set forth in the claims at the end of the specification.

10 In the drawings:—

Figure 1 is a front elevation of a furnace especially adapted for the burning of bituminous coal and provided with the present improvements.

15 Fig. 2 is a sectional side elevation of the same taken on the line 2—2 of Fig. 1.

Fig. 3 is a vertical section through the fuel feeding mechanism and inclosed chamber on the line 3—3 of Fig. 2.

20 Fig. 4 is a detail sectional view on the broken line 4—4 of Fig. 2 illustrating the ducts which lead from the preheated air chamber to the main combustion chamber.

Fig. 5 is a vertical section on the line 5—5 25 of Fig. 2.

Figs. 6 and 7 are sectional views similar to Fig. 3, but illustrating units of the fuel feeding mechanism applied to furnaces different in size from the one illustrated in

30 Fig. 3.

Like characters of reference in the several figures indicate the same parts.

The improvements of the present invention may be utilized in connection with a 35 furnace divided into a number of sections or divisions, by parting walls, the sections being assembled in a long line one after the other to form a battery of combustion chambers each of which may be equipped with a 40 grate or grates. It will be obvious that the number of divisions of the furnace is immaterial; in fact, one feature of my invention lies in the construction of the fuel feeding mechanism whereby it is readily adaptable to furnaces of varying widths. For 45 convenience in illustration and to avoid unnecessary complication, only one combustion chamber is shown in the accompanying drawings, said combustion chamber being 50 indicated by the reference character 1.

Within the chamber 1 is a grate 2 supported in an inclined position therein as shown more particularly in Fig. 2. The upper fuel receiving end of said grate is supported by 55 the lower girder member 3 of a double transverse bearer bar, the upper girder member 4 of said bar being utilized for a purpose which will hereinafter appear. The bearer bar extends clear across the combustion chamber and is supported by the side walls of the latter in any manner well known in the art. The lower end of the inclined grate may be supported in any suitable manner, and at said lower end there is arranged 60 a rocking section 5 preferably journaled to

oscillate in bearings formed in bearer bars bridged between the lower end of the grate and the forward member 6 of a series of transverse girders or beams, which support the rear wall 7 of the combustion chamber. 70

In its preferred construction the rocking section 5 is composed of rearwardly extending fuel supporting and dumping extensions and forwardly extending segmental sections. The movement of the rocking section of each 75 grate is controlled by an operating bar or link 9 pivoted to a downwardly extending arm 10 of the rocking section and extending out through the front wall of the furnace where said link is pivoted to a suitable operating lever arm 11, located outside the front furnace wall. Beneath the grate the bottom of the combustion chamber is extended by means of downwardly inclined flooring sections 12, 13, to form an ash pit 14 into 80 which the fire may be dumped, as required. The furnace illustrated in the drawings is particularly adapted for the burning of bituminous coal in thick heavy beds and therefore it is desirable that artificial draft 85 be supplied beneath the grate through an inlet 15 at the bottom of the ash pit.

The fuel receiving channel 16 is located at the forward end of the furnace directly in front of the inner vertical wall or plate 24 90 and the bottom of the channel is formed by a lower dead plate 19 inclined upwardly toward the front of the furnace and supported upon the triangular brackets 20 which are secured to and extend inwardly from the 100 rear face of the front furnace wall 17, as shown particularly in Fig. 2. To insure great rigidity and strength the innermost angular portions 20^a of the several brackets 20 are bolted to the forward girder member 105 4 of the transverse bearer bar hereinbefore referred to. From above the channel 16 is inclosed by the upper dead plate 23 which extends transversely clear across the furnace and is supported at its ends by the side 110 walls of the furnace as illustrated in Fig. 3. In the rear the upper dead plate 23 is supported upon the inner furnace wall 24 and extends over the the fire brick section 51 of the latter. The front edge of upper 115 dead plate 23 is spaced just enough above the inclined bottom of the channel 16 to provide a long narrow slot 17^a which extends clear across the channel 16 and through which hand tools may be inserted when it 120 is desired to assist the power operated rams in pushing the fuel deposited in the channel down to the fire bed. The lower dead plate 19 extends down to the fuel receiving end of the grate and said dead plate is preferably supported by the triangular bearing members 20 at an inclination corresponding substantially to the inclination of the grate. 125

In the embodiment illustrated power operated rams are employed for pushing the 130

fuel down onto the grate and the upper portion 19^a of the dead plate lies in a plane below the plane of the grate to provide a depressed channel in which the rams reciprocate while the lower portion 19^b of said dead plate is flush with the fuel bearing surface of the grate. The lower edge of inner furnace wall 24 is located above the plane of the dead plate 19 in order to permit the discharge of fuel, but at the same time the lower edge of said wall is set near enough to the plane of the dead plate in order to permit the formation of a ridge of fuel behind the wall 24. The upper end of the dead plate 19 projects through the transverse slot 17^a and mounted on said upper end is a ram cover 42, the upper face of which is preferably flush with the lower portion 19^b of the dead plate and consequently flush with the fuel bearing surface of the grate 2. As hereinbefore stated the front edge of upper dead plate 23 is spaced above the plane of the ram cover 42 so that a hand tool may be readily inserted into the channel at this point.

Beneath the cover is the ram 43, the construction of which has been set forth in detail in the application of William McClave. For present purposes it is sufficient to state that the reciprocatory motion is imparted to the ram by gear segments 44 fixed to a rock shaft 45, and having teeth which engage racks formed on the under surface of the ram. The rock shaft 44 is journaled in bearings extending upwardly from the front furnace wall 17 and is provided with a crank 46 pivoted to the upper end of a connecting rod 47. The latter in turn is pivoted at its lower end to a crank 48 on the main power shaft 34 whereby motion is transmitted to the gear segments 44 to reciprocate the ram and push the fuel in the channel 16 down to the grate below.

The present invention is particularly concerned with the mechanism for feeding fuel to the transverse channel 16 by gravity in such manner that transverse distribution of the fuel in the channel is effected solely by the gravitational feed or discharge of the fuel. For this purpose, it is essential that fuel be supplied to the channel 16 at a number of different points along the latter, and it is a feature of the present invention that such wide distribution of the fuel is effected without blocking the front of the furnace so as to make access to the interior thereof difficult. At spaced intervals, the upper dead plate 23 is provided with inlet openings 23^a, through which fuel is fed into the interior of the channel and seated over these openings are the branch chutes 52 of the fuel feeding sections or units 53. Each unit is provided with a main chute 54 and several branch chutes 52 and fuel deposited in the main chute will be directed into the several

branch chutes, which deliver the fuel through the inlet openings 23^a in the upper dead plate of the channel 16, the fuel spreading itself out by gravity in the channel into the path of the rams which push the fuel down to the grate. It will be understood that the main or entrance chute 54 of each section or unit is connected with the source of fuel supply, which may be located at some point above the furnace. By constructing the feeding mechanism in sections or units, the assemblage of the mechanism in proper position on the furnace is greatly facilitated and the mechanism is also capable of adaptation to channels and furnaces of varying widths by the simple process of adding or subtracting units to meet the particular requirements of the furnace to be equipped.

In order to adapt the feeding mechanism to furnaces of as many different sizes as possible, it will be found desirable to construct the units in different sizes, and, in the present embodiment two sizes of units are illustrated, one having three branch or discharge chutes 52 and the other having but two chutes. As one size unit has three branches and the other two, systems may be built up which differ from each other in the number of branches or discharge chutes by one branch only, so that practically every size or width of furnace can be readily accommodated. In the larger size unit, *i. e.*, the one having three branches 52, the two outer branches incline inwardly or converge into the main chute as shown at 52^a and the walls of the intermediate branch diverge as shown at 52^b to meet the inner converging walls 52^c of the outer branches. To insure delivery of fuel in substantially equal amounts to all members of the three-branch chute, an angular deflecting plate 55 is positioned in the main chute just beneath the inlet with the apex of the plate facing the inlet, as shown more particularly in Figs. 3 and 7. The smaller unit or two branch chute 110 is not provided with a deflecting plate 55 as the inner converging walls 52^c serve the purpose of deflecting fuel substantially in equal amounts to both branches. The outer walls 52^c of the two-branch chute converge in the same manner as do the corresponding walls of the three-branch chute, but at a slightly steeper inclination. It will be noted that open spaces 56 are left between the several branches 52 of the fuel feeding units, after the latter have been assembled over the dead plate 23 of the furnace, and these open spaces may be utilized for the location of fire doors, hereinafter described.

For controlling the discharge of fuel into the channel 16 from all branches 52 simultaneously, a gate 57 is positioned beneath the dead plate, consisting of an elongated plate having openings 58 adapted to register with the inlet openings 23^a of the dead plate. 130

The gate may be moved transversely to bring the openings 58 into and out of registry with the openings 23^a by means of a rod 59 secured to a block 60 mounted on the gate. 5 The rod 59 projects through a slot 61 formed in the side wall of the furnace whereby operation of the gate may be conveniently effected from the exterior of the furnace.

The fire brick section 51 extends upwardly behind the upper vertical wall 62 of the furnace, said wall being located to the rear of the fuel feeding sections or units, as shown in Fig. 2. The fire brick section is provided with openings or inlets 51^a which are respectively located behind the openings 56 interposed between the several branches or chutes 52. These openings 51^a permit access to the interior of the furnace and may be closed by fire doors 63 which are movable vertically in the space between the fuel feeding sections and the front furnace wall 62. Each fire door consists of a suitable metal plate 63^a provided with a forwardly projecting operating handle 63^b and if desired the metal plate may be lined with fire brick 63^c, as shown in Fig. 2. Vertical slideways 64 are provided receiving the vertical edges of the several fire doors and the lowering and lifting movement of said doors is preferably facilitated by counterweights 65 secured by ropes or cords 66 to the respective doors. The ropes 66 run over pulleys 67 pivotally mounted in the front furnace wall 62. A door may be readily lifted by means of the handle 63^b which projects from the front, the several doors being controlled independently of each other.

Above the fire brick section 51 is a space 68 inclosed by the rear upper fire brick section 69, the top plate 70 and the front wall 62. This space 68 constitutes a preheated air chamber which is adapted to receive air from beneath the grate by a suitable duct. The chamber 68 communicates with the upper portion of the combustion chamber by means of ducts 71, between fire brick sections 51 and 69, as shown in Fig. 4.

Figs. 6 and 7 illustrate the mode of applying the fuel feeding units of this invention to furnaces of different widths. In Fig. 6 the furnace is smaller than the one disclosed in Figs. 1 to 5, inclusive, and hence upper dead plate 23 is provided with four discharge openings 23^a instead of five. Two of the smaller size units, *i. e.*, each unit having but two branches 52 are provided, the units being secured in position over the dead plates. In Fig. 7 the furnace is still smaller having but three discharge openings in the dead plate 23. In this case it is only necessary to employ a single fuel feeding unit of the larger size having three branches 52.

What is claimed is:—

65 1. A furnace construction comprising the

combustion chamber, the grate supported within the combustion chamber, a substantially inclosed fuel receiving channel within the furnace extending substantially clear across in front of the fuel receiving end of 70 the grate, means for delivering fuel by gravity to the channel at different points along the latter and fire doors in the front furnace wall interposed between the points of delivery of the fuel to the channel, said 75 doors being located above the fuel receiving channel whereby the continuity of the latter is unbroken.

2. A furnace construction comprising the combustion chamber, the grate supported 80 within the combustion chamber, a substantially inclosed fuel receiving channel within the furnace extending substantially clear across in front of the fuel receiving end of the grate, means for delivering fuel by 85 gravity to the channel at different points along the latter and vertically movable independently operable fire doors in the front furnace wall interposed between the points 90 of delivery of the fuel to the channel, said doors being located above the fuel receiving channel whereby the continuity of the latter is unbroken.

3. A furnace construction comprising the combustion chamber, the grate supported 95 within the combustion chamber, a substantially inclosed fuel receiving channel within the furnace extending substantially clear across in front of the fuel receiving end of the grate, means for delivering fuel by 100 gravity to the channel at different points along the latter and vertically movable fire doors in the front furnace wall interposed between the points 105 of delivery of the fuel to the channel, said doors being located above the fuel receiving channel whereby the continuity of the latter is unbroken.

4. A furnace construction comprising the combustion chamber, the grate supported 110 within the combustion chamber, a substantially inclosed fuel receiving channel extending substantially clear across in front of the grate and having inlet openings at intervals in the top of the channel, said channel having a transversely extending 115 opening in its front and rear walls substantially coextensive with said walls, and a fuel feeding unit having a plurality of delivery branches adapted to register with a corresponding number of said inlet openings. 120

5. A furnace construction comprising the combustion chamber, the grate supported within the combustion chamber, a substantially inclosed fuel receiving channel extending substantially clear across in front 125 of the grate and having inlet openings at intervals in the top of the channel, said channel having a transversely extending opening in its front and rear walls substantially coextensive with said walls, and a 130

- fuel feeding unit having a main inlet branch and a plurality of discharge branches adapted to register with a corresponding number of said inlet openings.
6. A furnace construction comprising the combustion chamber, the grate supported within the combustion chamber, a substantially inclosed fuel receiving channel extending substantially clear across in front of the grate and having inlet openings at intervals in the top of the channel, said channel having a transversely extending opening in its front and rear walls substantially coextensive with said walls, and fuel feeding mechanism embodying a plurality of units each having a main inlet branch and a plurality of discharge branches adapted to register with a corresponding number of said inlet openings.
7. A furnace construction comprising the combustion chamber, the grate supported within the combustion chamber, a substantially inclosed fuel receiving channel extending substantially clear across in front of the grate and having inlet openings at intervals in the top of the channel, a fuel feeding unit having a plurality of spaced delivery branches adapted to register with a corresponding number of said inlets, and fire doors in the front furnace wall interposed between the several branches of the fuel feeding unit.
8. A furnace construction comprising the combustion chamber, the grate supported within the combustion chamber, a substantially inclosed fuel receiving channel extending substantially clear across in front of the grate and having inlet openings at intervals in the top of the channel, a fuel feeding unit having a plurality of spaced delivery branches adapted to register with a corresponding number of said inlets, and vertically-movable fire doors in the front furnace wall interposed between the several branches of the fuel feeding unit.
9. A furnace construction comprising the combustion chamber, the grate supported within the combustion chamber, a substantially inclosed fuel receiving channel extending substantially clear across in front of the grate and having inlet openings at intervals in the top of the channel, a fuel feeding unit having a plurality of spaced delivery branches adapted to register with a corresponding number of said inlets, and independently operable fire doors in the front furnace wall interposed between the several branches of the fuel feeding unit.
10. A furnace construction comprising the combustion chamber, the grate supported within the combustion chamber, a substantially inclosed fuel receiving channel extending substantially clear across in front of the grate and having inlet openings at intervals in the top of the channel, a fuel feeding unit having a plurality of spaced delivery branches adapted to register with a corresponding number of said inlets, a furnace wall behind the fuel feeding unit having openings registering with the spaces between the branches of the unit, a corresponding number of said inlets, a furnace wall behind the fuel feeding unit having openings registering with the spaces between the branches of the unit, and fire doors for covering the openings in said vertical wall, the fire doors and the openings in the furnace wall being located above the fuel receiving channel, whereby the continuity of said channel is unbroken.
11. A furnace construction comprising the combustion chamber, the grate supported within the combustion chamber, a substantially inclosed fuel receiving channel extending substantially clear across in front of the grate and having inlet openings at intervals in the top of the channel, a fuel feeding unit having a plurality of spaced delivery branches adapted to register with a corresponding number of said inlets, a furnace wall behind the fuel feeding unit having openings registering with the spaces between the branches of the unit, and vertically-movable fire doors for covering the openings in said vertical wall, the fire doors and the openings in the furnace wall being located above the fuel receiving channel, whereby the continuity of said channel is unbroken.
12. A furnace construction comprising the combustion chamber, the grate supported within the combustion chamber, a substantially inclosed fuel receiving channel extending substantially clear across in front of the grate and having inlet openings at intervals in the top of the channel, a fuel feeding unit having a plurality of spaced delivery branches adapted to register with a corresponding number of said inlets, a furnace wall behind the fuel feeding unit having openings registering with the spaces between the branches of the unit, vertically movable fire doors for covering the openings in said vertical wall, and counterweights secured to said fire doors for assisting in the operation of the latter, the fire doors and the openings in the furnace wall being located above the fuel receiving channel, whereby the continuity of said channel is unbroken.
13. A furnace construction comprising the combustion chamber, the grate supported within the combustion chamber, a fuel receiving channel extending substantially clear across in front of the fuel receiving end of the grate, said channel having a transversely extending opening in its front and rear walls substantially coextensive with said walls, and fuel feeding mechanism for delivering fuel to said channel at intervals along the latter, embodying a plurality of fuel feeding units, each having a plurality of discharge branches adapted to be positioned over said channel to effect the gravitational discharge of fuel therein.
14. A furnace construction comprising

the combustion chamber, the grate supported within the combustion chamber, a substantially inclosed fuel receiving channel within the furnace extending substantially clear across in front of the fuel receiving end of the grate, said channel having a transversely extending opening in its front and rear walls substantially coextensive with said walls, means for delivering fuel by gravity to the channel at different points along the latter, and means for controlling the fuel discharge simultaneously at all of said points.

15. A furnace construction comprising the combustion chamber, the grate supported within the combustion chamber, a substantially inclosed fuel receiving channel extending substantially clear across in front of the grate, said channel having openings in its top wall and a transversely extending opening in each of its front and rear walls substantially coextensive with said front and rear walls, fuel delivery chutes mounted over said openings whereby fuel may be dis-

charged by gravity into the channel at 25 different points along the latter, and a gate for opening and closing all of said openings simultaneously.

16.. A furnace construction comprising the combustion chamber, the grate supported within the combustion chamber, a substantially inclosed fuel receiving channel extending substantially clear across in front of the grate, said channel having openings in its top wall and a transversely extending 30 opening in each of its front and rear walls substantially coextensive with said front and rear walls, fuel delivery chutes mounted over said openings whereby fuel may be discharged by gravity into the channel at 35 different points along the latter, a slideable gate mounted in said channel adapted to open and close all of said openings simultaneously and means extending through the side wall of the furnace for operating said 40 gate.

WILLIAM R. McCLAVE.
